UNITED STATES PATENT OFFICE.

RICHARD COAD, OF KENNINGTON, ENGLAND, ASSIGNOR TO SAMUEL GRIFFITH FISHER,
OF MOBILE, ALABAMA.

COMBUSTION OF FUEL.

Specification of Letters Patent No. 6,446, dated May 8, 1849.

To all whom it may concern:

Be it known that I, RICHARD COAD, of 5
Kennington, Surrey, England, a subject of
the Queen of Great Britain, have invent-
ed or discovered new and useful Improve-
ments in the Combustion of Fuel and in
Applying the Heat so Obtained; and I, the
said RICHARD COAD, do hereby declare that
the nature of my said invention and the
10 manner in which the same is to be per-
formed are fully described and ascertained
in and by the following statement thereof,
reference being had to the drawings here-
unto annexed and to the figures and letters
15 marked thereon, that is to say—

My invention consists of improvements
in the construction of furnaces for the bet-
ter combustion of fuel and for applying the
heat so obtained. And in order that my
20 invention may be most fully understood
and readily carried into effect I will pro-
ceed to describe the drawings hereunto an-
nexed.

Description of the drawings: Figure 1
25 shows a front section of a furnace construct-
ed according to my invention applied to a
steam boiler. Fig. 2 is a side section of the
same. Fig. 3 shows a plan in section of the
same and Fig. 4 a plan thereof.

30 In each of these figures the same letters
indicate similar parts.

In this arrangement there are two furnaces *a* and *b* divided by an air chamber *c* the fire brick or suitable stone *d*, *d*, which
35 form the partitions between the air chamber *c* and the furnaces being perforated as
shown for supplying the two fires with heat-
ed air above the fuel under combustion the
air being supplied by an opening *e* to the
40 air chamber *c* or by other convenient means
and it will be evident that the air before
it can arrive into the furnaces will have
become highly heated owing to having to
pass through the highly heated fire brick
45 of the partitions *d*, *d*, and therefore the
oxygen will be in a better condition to com-
bine with the products of the fuel not al-
ready ignited and when desired steam may
also be admitted into the air chamber by
50 the pipe *f*. It will be seen that the fire
is inclosed at all parts by reticulate parti-
tions *g*, *g*, similar to those through which
the air passes from the air chamber and
the upper part of the furnace and these
55 partitions and upper part of the furnaces
made of perforated lump or stone fire brick
will at all times be highly heated and cause

all the products of the fuel to be ignited
before passing away from the furnace.

I have in the drawings shown the particu- 60
lar formation of the perforations of the fire
brick which I prefer. I would however
state that the shape of the perforations may
be varied. *h*, *h*, are the fire doors. *i*, *i*, the
ash pits. *j*, *j*, are the fire backs. I would 65
remark that it has heretofore been pro-
posed in constructing furnaces to have the
sides so arranged as to admit both cold and
heated air to the furnace and I mention
this fact in order to state that I do not 70
claim the same and the peculiarity of my
invention consists in causing a furnace to
be so arranged that the heat and flame shall
pass through numerous openings through
fire brick as explained so as to insure the 75
whole of the products evolved from the fuel
being ignited.

It will be seen that by having the perfor-
ated partitions at the sides of the furnaces
and also at the end as well as at top, the 80
heat passes off laterally as well as at the end
and upward through the top and then acts
on the boiler or other surface to be heated.

I have in the drawings shown the furnaces
to be fed with feeding apparatus, such 85
as is well known. I do not therefore make
any claim thereto.

I have in the figures of the drawings
above referred to shown a convenient con-
struction of tubular steam boiler, which may 90
be used with the furnaces above described.
I do not however make any claim thereto,
nor have I thought it necessary to show the
several parts of such boiler, the same being
well understood. It is not necessary in 95
each case that two furnaces should be com-
bined together as shown in the figures of
the drawings above described, as single fur-
naces may be made according to my inven-
tion.

100 Figure 5 shows a plan in section of a
single furnace constructed according to my
invention, the air chamber being in front
as shown and there are reticulate partitions
of fire brick lump or suitable stone through 105
which the heat and flame passes on either
side as well as at the end and top which
parts are to be constructed as described in
respect to the like parts in the previous fig-
ures, except that the fire brick top will re- 110
quire to be arched instead of flat as in the
former instance.

Fig. 6 shows a front view, Fig. 7 a trans-
verse section, and Fig. 8 a longitudinal sec-

tion of an arrangement of furnace for those constructions of steam boilers where the fire place is within the boiler. The boiler shown in these figures is cylindrical but this may 5 be varied. This arrangement of furnace so far as its reticulate character is concerned is similar to the ones previously described; it differs only in shape. The same letters of reference are used to indicate similar 10 parts and the description above given will apply to the present figures.

Though I have thus far described my improvement in the combustion of fuel and in applying the heat so obtained, with reference 15 to one only of the purposes for which heat is required, viz, the generation of steam, yet as the application of heat when once generated may be made to any object requiring to be heated, so, I do not limit myself 20 to any particular object or material to be heated, or to any particular state or form of such material. Thus if instead of applying the heat of my furnace to the surface of a steam boiler I have occasion to heat the 25 surface of a gas retort I shall construct the inclosing arches or reticulate partitions on the same principles as those seen in Figs. 1, 2, 3, 5, 7, or 8.

Should the object be the heating of pipes 30 conveying currents of air or water the great principle of my invention will still be to interpose between the fire and the objects to be heated a fire brick partition perforated with numerous holes of suitable form and 35 dimensions to permit a circulation through them of the products of combustion and of air admitted above the fire. When the heating or the melting of iron is the application to be made of the heat I shall use my furnace 40 constructed in all essential points on the same principle as if the object were the generation of steam. In doing this I do not wish to be understood to claim as my invention any particular form of reverberatory 45 or other furnace. The fire brick wall contained within an air chamber and having numerous perforations on the sides and a reticulated partition beyond or back of the fire and also over the top when necessary, 50 for the purpose of permitting air to pass above the grate, through a highly heated fire brick and there to come in contact with the fuel also in a highly heated state and accompany the volatile combustible fuel 55 through the reticulate partition are the principal features of my improvement. This modification of my invention is seen in Figs. 9, 10, 11 and 12 where *k* is the air chamber corresponding to that seen at *c*, Fig. 1, *d*, *d*, 60 &c. are the fire brick walls corresponding to those with the same letter of reference in Fig. 1, and *l*, *l*, are the holes through which air gains admittance from the air chamber above as already described, and *P* is the reticulated brick partition between the fire *m*,

and the material to be heated at *s*. In using my furnace for steam boilers or for any other purpose, I either allow the air to flow from the air chamber by the mere draft of the chimney or shall force it by mechanical 70 means through suitable pipes and channels as *o*, Fig. 10.

When the application of heat is to be made to pipes for circulating hot water the same principles are observed and the firebrick 75 partition between the fire and the surfaces of the tubes to be heated, may be perforated with holes as already described or may have narrow slots between the several pillars of fire-clay *r*, *r*, *r*, Figs. 14, 15, 16, and 17, 80 through which the flame will reach the tubes *s*, *s*, *s*. In this case the fire may be entirely inclosed within the fire-brick casing as in Figs. 1, 2, and 3, or as a modification, it may be open in front, in which case the perforated brick partition for the air to pass through will be partly above the mass of fuel as seen at *u*, *u*, Figs. 14, and 16. The principle of combining gas-passages through fire brick partitions with air passage through 85 similar materials, whereby the volatile portions of the fuel and the air by which they are to be supplied are both heated to a high temperature before they come in contact with the surfaces or objects to be heated is 90 95 alike applicable not only to the several purposes cited as illustrations or modifications of my improvement, but to many others which I do not think it necessary specifically to point out as they are generally understood.

I do not intend to claim as my invention any particular form of steam boiler, reverberatory furnace, or water or air heating system of tubes, and I would have it understood that I do not confine myself to the details herein described so long as the peculiar character of my invention be retained. Nor do I claim the mere admission of air heated or cold above the fire bars, as 100 105 I am aware that this has already been done; but

What I do claim is—

The mode of constructing furnaces whereby numerous streams of air are caused to 115 pass above the fire bars through perforated fire brick lump or suitable stone at the sides top and front of such furnaces, in combination with the arrangement for making the products of combustion pass through and 120 beyond reticulate partitions of the same materials, before they come in contact with the surfaces or objects intended to be heated, in the manner and for the purposes substantially as herein set forth.

RICHARD COAD.
